UNITED STATES PATENT OFFICE.

STEPHEN E. PARRISH, OF HILSDALE, MICHIGAN.

WINDING AND MEASURING DEVICE.

No. 856,289.

Specification of Letters Patent.

Patented June 11, 1907.

Application filed November 24, 1906. Serial No. 344,869.

To all whom it may concern:

Be it known that I, STEPHEN E. PARRISH, a citizen of the United States of America, residing at Hillsdale, in the county of Hillsdale and State of Michigan, have invented certain new and useful Improvements in Winding and Measuring Devices, of which the following is a specification, reference being had therein to the accompanying drawings.

10 My invention relates to new and useful improvements in devices for reeling lace, ribbon, tape and other similar articles, and consists first, in the novel construction and arrangement of parts by which lace or other material may be wound on a reel or bolt, and, 15 secondly, in means whereby the length of material thus wound on the bolt may be quickly and easily computed, as will be more fully hereinafter described and set forth in 20 the claims.

In the drawings, Figure 1 shows a perspective view of the device as in use; Fig. 2 is a plan view of the registering mechanism; Fig. 3 is an elevation of one of the adjustable spindles; Fig. 4 is a sectional view on lines 4—4 of Fig. 3; Fig. 5 is an elevation of a modified form of spindle; Fig. 6 is a vertical central section of Fig. 5; Fig. 7 is a side elevation of the device in the folded position; and Fig. 8 25 is a side elevation of the device as in operation.

The supporting frame A comprises pairs of spaced parallel arms B B' and C C', connected by horizontal members b and c respectively. The arms B and C are pivotally connected at D, and the arms B' and C' are similarly connected, so that the device when not in use may be folded as shown in Fig. 7.

As a removable base for the frame, I preferably provide transverse strips E E, detachably secured to the members b and c by means of thumb screws e.

In the upper ends of the arms B and C are journaled spindle sections F and F' respectively. The arm B preferably has its upper end down-turned at b' so as to form two bearings for the section F, and a crank G is secured to the outer end of said section.

Journalled in the upper ends of the arms B' and C' and alined with the sections F and F' respectively are longitudinally adjustable spindle sections H, and to give sufficient bearing length I preferably secure a tubular member c' to each of said arms.

55 On the inner ends of all four sections are clamps comprising a U-shaped member I,

having its ends suitably secured, as by the rivets j, to the segmental spring J, tending to draw together the gripping jaws K and K'. For operating the clamp I provide the members k and k', which are secured to the jaws K and K' respectively and project through apertures in the member J. It will thus be seen that the edge of the aperture forms a fulcrum for the gripping jaws, and by pressing together the members k and k' the clamp may be released.

L is a sprocket secured to the section F between the bearings, and L' is a sprocket of the same diameter secured to the outer end 60 of the section F'. M M are idlers journaled on the arm B at points above and below and equidistant from the pivot D, and N is an endless chain engaging said sprockets and idlers. By having the idlers M M equidistant 65 from and above and below said pivot, the chain will be held taut in the folded as well as in the open position of the frame.

For registering the number of rotations of the spindle F, a toothed wheel O is journaled 70 near the end of the arm B, and provided with a suitably marked dial face o. This wheel is arranged to be engaged and moved a distance of one tooth at each revolution of the spindle by means of a lug O' on said spindle 75 and engaging said teeth.

P is the bolt on which is wound the lace Q which it is desired to measure, and this bolt is placed in the clamps on the spindle sections F' and H. An empty bolt P is secured in the 80 other pair of clamps, and the free end of the lace being attached or held on the bolt P the crank G is turned and the lace is unwound from the bolt P' and wound on the bolt P. When it has been wound in this manner, the 85 dial will register the number of revolutions of the bolt P, and this number, multiplied by the distance around said bolt, will give the approximate length of the lace. For instance, supposing the bolt to be six inches 90 wide and the number of revolutions to be twenty, it is obvious that the length of the lace is substantially twenty feet. While the exact length is not determined in many instances, the approximate will answer, as in 95 taking an inventory of stock, where the approximate length of each piece of goods must be determined.

It will be seen that the position of the idlers M carries the chain out of the horizontal place of the sprockets L and L', and in fact the line of the chain is substantially par-

allel with the arms B and C. For this reason, the operator is enabled to reach the lace and guide it while it is being wound on the bolt P without conflicting with the chain.

- 5 When it is desired to measure goods wound on a spool, such as ribbon or tape, the section H is removed from the arm C', and the modified form of spindle section R shown in Figs. 5 and 6 is substituted therefor. This spindle 10 is provided with an eye R' at one end, which is pivoted on a staple S secured to the circular plate S'. On the back of this circular plate is a diametrically arranged fin T having extended ends T' arranged to be clamped by the jaws K K' on the section F'. The section R is passed through the spool U, and an annular disk V reinforced by the disk V' is placed on the section to limit the longitudinal movement of said spool. These disks are 15 preferably backed by a rubber washer W closely, but detachably, fitting the section R. While the spool is being unwound it is preferably permitted to turn freely on the spindle, but when the ribbon is re-wound 20 thereon the spool must be positively rotated. I therefor make the sides r of the eye R' wedge-shaped, and force the spool tightly thereon, whereby it is caused to rotate with the spindle.
- 25 30 It will be seen that the device may be set up on the end of a counter or table, and the slack from the reels may be permitted to fall thereon, and the operator can easily guide the material as it is wound on the measuring reel P' or rewound upon the reel P or the spool U.

While I have shown and described the device with two reels and the computing mechanism, it is obvious that I may use only the 40 support B B' and the spindle sections thereon and either remove or disregard the computing mechanism. When used in this way lace, ribbon, or other strip material may be wound upon the reel P' and it is obvious that any 45 reel or board on which it is usual to wind such materials may be attached to the spindle by the clamps K. The material may be quickly wound thereon and the reel removed and replaced by another.
